US0D1086042S

(12) **United States Design Patent** (10) **Patent No.:** **US D1,086,042 S**
(45) **Date of Patent:** **** Jul. 29, 2025**

(54) **CHARGING CASE FOR WIRELESS EARBUD**

(71) Applicant: **LG ELECTRONICS INC.**, Seoul (KR)

(72) Inventors: **Jinki Min**, Seoul (KR); **Youngsoo Han**, Seoul (KR); **Dongsoon Kim**, Seoul (KR)

(73) Assignee: **LG ELECTRONICS INC.**, Seoul (KR)

(**) Term: **15 Years**

(21) Appl. No.: **35/520,785**

(22) Filed: **Nov. 10, 2023**

(80) **Hague Agreement Data**

Int. Filing Date: **Nov. 10, 2023**
Int. Reg. No.: **DM/234733**
Int. Reg. Date: **Nov. 10, 2023**
Int. Reg. Pub. Date: **May 10, 2024**

(30) **Foreign Application Priority Data**

Jun. 30, 2023 (KR) 30-2023-0025282
(51) **LOC (15) Cl.** **13-02**
(52) **U.S. Cl.** ..... **USPC** **D13/108**

(57) **CLAIM**

The ornamental design for a charging case for wireless earbud as shown and described.

DESCRIPTION

1. Charging case for wireless earbud

1.1 : Perspective view

1.2 : Front view

1.3 : Back view

1.4 : Left view

1.5 : Right view

1.6 : Top view

1.7 : Bottom view

1.8 : Perspective view; showing the design in an open configuration

1.9 : Back view; showing the design in an open configuration

1.10 : Left view; showing the design in an open configuration

1.11 : Bottom view; showing the design in an open configuration

The characteristic features of the design lie in the shape; reproductions 1.8 to 1.11 show the state of use; the broken lines indicate portions of the article that form no part of the

(Continued)

claimed design; the broken lines shown in reproduction **1.8** illustrate environmental structure and form no part of the claimed design.

1 Claim, 11 Drawing Sheets
